PHYSICAL CULTURE MACHINE

William S. Hawley, Newark, N. J.

Application September 30, 1936, Serial No. 103,310

4 Claims. (Cl. 128—25)

This invention relates to physical culture machines, and particularly to an improved machine for exercising different parts of the body by compulsory swinging motion of the body or the parts thereof.

Another object of the invention is to provide a physical culture or exercising machine wherein the neck and torso may be exercised while the legs remain quiet or the reverse may take place.

An additional object of the invention is to provide a physical culture device where the body of a person is clamped in place and then mechanically moved to exercise the body, stretch the spine, and exercise the various limbs either at the same time or at different times.

In the accompanying drawings:

Fig. 1 is a side view of one section of an exercising machine disclosing certain features of the invention;

Fig. 2 is a top plan view of the construction shown in Fig. 1;

Fig. 3 is a side view similar to Fig. 1 but showing the parts in different position;

Fig. 4 is a fragmentary sectional view showing the adjustable feature of the leg supporting yoke;

Fig. 5 is an enlarged sectional view through Fig. 2 approximately on the line 5—5;

Fig. 6 is a bottom plan view of the center part of the structure shown in Fig. 5, said view illustrating how the circuit of the motors is opened when the parts are moved to a certain position;

Fig. 7 is a fragmentary sectional view through Fig. 2 on the line 7—7;

Fig. 8 is a view of the complete machine with the parts shown in Fig. 1 in section and illustrating two positions of the body of a person using the machine;

Fig. 9 is a top plan view of the leg exercising part shown in Fig. 8.

Referring to the accompanying drawings by numerals, 1 indicates a frame which may be wood, metal or other material and may have suitable cross braces so that means are presented for supporting the various moving parts. On top of the frame 1 is arranged a table 2 which may be rigidly secured in place and which has an auxiliary table 3 connected therewith by a suitable hinge 4. A pad 5 preferably of rubber is cemented or otherwise rigidly secured to the auxiliary table 3. A pad 6 preferably of rubber is secured near one end to the table 2 while at the other end it is loose whereby the seat 7 of the leg exercising part 8 may be readily positioned as shown in Fig. 8. 55 The torso exercising part as shown in Fig. 3 is

provided with a pair of brackets 9 each carrying a pivotal bolt 10 on which certain parts are pivotally mounted as hereinafter fully described.

As shown in Figs. 1 and 2, a bar 11 is provided for each of the bolts 10 and is pivotally mounted thereon. One end of bar 11 is pivotally connected at 12 with a link 13, while the opposite end of the bar is preferably rounded and provided with a number of apertures or bores 11' as shown in Fig. 4. These apertures or bores are adapted to receive the pin 14 held by a spring 15, which spring is riveted at 16 to the U-shaped member 17. A slide ring 18 acts to hold the pin 14 in any of the apertures 11'. This ring is held in place by friction but may be readily shifted when desired to move the outer end of the U-shaped member 17 toward or from the bolts 10. The U-shaped member 17 is really an exercising frame and carries straps 18 and 19 as shown in Fig. 2 and also a fitting 20 to which one end of a spring 21 is connected. The opposite end of spring 21 is connected to a strap 22 which is formed in two parts and connected together by an adjusting buckle 23. The strap 22 is connected with a head harness 24 as shown in Fig. 8. The harness 24 is provided with a suitable portion extending around the head at the forehead, a suitable strap portion under the chin, and other strap portions at the back and top of the head whereby the head may be pulled and supported through the action of the spring 21 and associated parts. The straps 18 and 19 are provided with adjustable buckles and also with wrist straps 25 and 29 having buckles whereby the straps may be properly clamped around the wrists of the arms of a person using the device. The parts are preferably proportioned and adjusted so that the body of a person when lying on the table 2 will have the center of the hips opposite the respective bolts 10.

Associated with each of the bolts 10 is a bar 30 having one section extending into the U-shaped frame 31 in a similar manner to that illustrated in Fig. 4. The opposite end of the bar 30 is provided with a pivotal pin 32 whereby it is pivotally connected with the link 33. It will be understood that bar 30 in a similar manner to bar 11 has a central apertured enlargement whereby it is freely rotatable on the bolt 10 which acts as an axle therefor. It will be noted that by reason of the construction shown in Fig. 4 the respective frames 17 and 31 may be adjusted to suit different sized persons. Suitable straps 34 are provided for each of the feet of the person using the device whereby the feet may be strapped to 55

the cross bar 31' of the frame 31. When the head and arms are arranged as shown in Fig. 1 and also the feet are strapped to the cross bar 31' and the parts are in proper position to give a desired exercise to the patient, by swinging the frame 17 upwardly and downwardly the body of the patient will be swung upwardly to the dotted line position shown in Fig. 1 and then back to the full line position. This will give a desired exercise to the torso and also a desired strain on the neck and back. After the torso and associated parts have been thus exercised, the frame 17 is left in a horizontal position as shown in Fig. 3 and then frame 31 is swung upwardly and downwardly. This will give a desired exercise to the lower legs and also the thigh portions without any effort on the part of the patient. In order to cause the frames to swing as just described, suitable power means have been connected to the respective links 13 and 33. It will be understood that both sides of the device have the same arrangement of links, bars and associated parts so that the description of one side will apply to both sides.

As illustrated in Fig. 3, one end of link 13 is pivotally mounted at 35 to a crank 36 rigidly secured to the shaft 37 carrying pulley 38. This pulley is actuated by a belt 39 passing over a small pulley 40 rigidly secured to shaft 41. A worm wheel 42 is also rigidly secured to shaft 41 and continually meshes with the worm 43 which is driven by the electric motor or other power element 44. In this way the pulley 38 is driven by a belt, and if unusual strain is brought to bear on the link 13 and other parts this belt will slip so that the patient will not be injured. Link 33 which is associated with frame 31 is pivotally mounted at its outer end to crank 45 by a pivotal pin 46. Crank 45 is rigidly secured to the shaft 47 which in turn is rigidly secured to pulley 48. Belt 49 passes over pulley 48 and also over pulley 50 which is rigidly secured to shaft 51. A pulley 52 is also rigidly secured to shaft 51 and accommodates the belt 53 which passes over the driving pulley 54, which driving pulley is rigidly secured to shaft 55. A worm wheel 56 is also rigidly secured to shaft 55 and continually meshes with the worm 57 which is driven by the electric motor or other power element 58. It will therefore be seen that when either of the power elements 44 or 58 are used motion is transmitted through certain belts whereby a slippage may be had if there is an unusual resistance.

When it is desired to swing the frame 31 upwardly and downwardly, current is turned on to the motor 44 and by the reduction in gearing above set forth frame 31 will swing upwardly and downwardly at a desired speed. After this part of the exercise has been completed, current is turned off of the motor 44 and turned on to the motor 58, whereupon the frame 17 will swing upwardly and downwardly. These two frames do not swing at the same time. By having the head, arms and legs all strapped to the respective frames, the entire body is under some tension at all times and when the machine is caused to function the body will be exercised while under tension. Removable guards 59 and 60 are arranged on each side of the table 2 so that the body can not come in contact with any of the moving parts. After the desired exercise has been completed the feet, head and arms may be released and the auxiliary table 3 moved up to the position shown in Fig. 5. This will allow the attendant to massage the patient while lying on the tables 2 and 3.

As a safety matter the circuit of the motors 44 and 48 includes the safety switch 61 which is shown in diagram in Fig. 6. This switch includes terminals 62 and 63 and a slide connector 64 held by suitable straps 65 to the bottom of the table 2. A suitable link structure 66 connects member 64 with a bracket 67 carried by the auxiliary table 3. When the auxiliary table 3 is in a horizontal position, member 64 will be moved away from or out of contact with the terminals 62 and 63. It will thus be seen that the power elements are deprived of current during the massaging operation. It will also be understood that suitable switches are provided for each of the motors so that they may be turned on or off manually at any time in addition to the automatic switch shown in Fig. 6.

In providing an exercise for the body of the patient, it is not only desirable to have the movements produced by the frames 17 and 31 but in addition a back and forth movement of the legs. To secure this result a leg exercising structure 68 is provided and is shown particularly in Figs. 8 and 9 of the drawings. This part is formed with a suitable frame 69 of metal or other material and formed with a loop member 70 at the bottom adapted to be engaged by the hooks 71 whereby the frame 69 may be held in operative position. The hook member 71 is connected with a pivotally mounted shaft 72 having a suitable handle 73 whereby the hook member may be raised or lowered as desired. It will be understood that one, two or more hooks 71 may be connected with the shaft 72. The frame 69 at the top is provided with an extension 74 which is deflected downwardly and then horizontally so as to receive the seat 7, which seat is adapted to be inserted beneath the pad 6 when the leg exercising part 68 is in use.

A traveling platform 75 is mounted on the top bars 76 and is adapted to be moved toward and from the frame 1. In order to secure this result and at the same time hold the platform 75 in a desired adjusted position, there is provided a screw 77 having a suitable crank 78 and extending through a traveling nut 79 which is secured in any desired manner to the platform 75. When the crank 78 is rotated the platform will be moved in one direction or the other, according to the direction of rotation of the screw 77. Suitable brackets are carried by the platform 75 whereby a crank shaft 80 is supported and on this crank shaft is mounted a pulley 81. Connected with the crank shaft 80 are cranks 82 and 83 and these cranks at their outer ends carry pedals 84 and 85 which may be ordinary bicycle pedals. A belt 86 passes over the pulley 81 and also over a driving pulley 87, which driving pulley is rigidly secured to shaft 88. A worm wheel 89 is also secured to the shaft 88 and continually meshes with the worm 90 driven by the electric motor 91. Motor 91, pulley 87 and associated parts are carried by a bottom platform 92 which slides on the bars 93 forming the lower part of frame 69. A traveling nut 94 is rigidly secured to the lower platform 92 and is caused to move by the fixed screw 95 which has a crank 96.

When the feet of a patient are strapped to the pedals 84 and 85, crank 78 is actuated until these pedals are a correct distance from the frame 1 to permit the patient to properly turn the crank shaft 80. The lower platform 92 is likewise adjusted. After the parts have been adjusted the motor 91 is caused to function and the power therefrom will rotate the crank shaft 80 and as-

sociated parts and cause the feet and legs of the patient to move as if they were operating a bicycle. The torso may be resting on the table 2 when this takes place or, if desired, it could be 5 raised to the dotted position shown in Fig. 8 whereby a more strenuous exercising movement will be secured. By using all parts of the exercising machine substantially all parts of the body of a person will be exercised, and in addition the 10 spine will be pulled which secures certain desirable results. The exercise compelled by the machine is rather strenuous and consequently any one of the exercising movements can only be carried out for a very short period at one time, as 15 for instance two or three minutes. After all parts have been exercised as described, it is usually desirable for the patient to rest on the tables 2 and 3 and have an attendant massage the parts to a greater or less extent. It will also be noted 20 that during the exercising of all parts of the body the weight is supported but the body is under tension during the movements produced by the machine.

From Fig. 7 it will be noted that when the auxiliary platform 3 is raised it may be locked in a raised position by a suitable slide 2' carried in suitable brackets 2''.

I claim:

1. A physical culture machine including a frame having a table at the top thereof adapted to receive the torso of a person, a swinging frame carried by the first mentioned frame, said table being adapted to receive a patient with his hips at the axis of said swinging frame, means including a spring for connecting the head of the person to the end of said frame opposite the pivotal end, and adjustable means for connecting the arms to the same end of said frame with the hands extending beyond the head.

2. A physical culture machine including a platform for receiving the head and torso of a patient, a leg exercising frame and a torso exercising

frame, said frames being pivotally mounted at the same point, said platform being adapted to receive a patient with his hips at the axes of said exercising frames, whereby said frames are swingable from an axis coincident with the axis 5 of the swinging movement of the patient, means for connecting the head and arms of the patient to the torso exercising frame at the end opposite its pivotal mounting, and means connecting the feet to the leg exercising frame at the end opposite 10 its pivotal mounting.

3. A physical culture machine including a supporting table adapted to support the torso and head of a patient, a pair of brackets connected with said table, a U-shaped exercising frame 15 having the free ends pivotally mounted on said brackets, said table being adapted to receive a patient with his hips at the axis of said exercising frame, adjustable means for connecting the head of the patient with the cross bar of the U-shaped 20 frame, adjustable means for stretching the arms above the head and connecting the wrists to said cross bar, a link for swinging said frame from a horizontal to a substantially vertical position and then back again, a crank for actuating said link, 25 and power means for driving said crank.

4. A physical culture machine including a platform for receiving the torso and head of a patient, a pair of brackets secured to said platform, an exercising frame pivotally mounted on said 30 brackets, said frame being substantially U-shaped, means for connecting the wrists and head of the patient to the closed end of the frame, a leg exercising frame, means for connecting the leg exercising frame with said platform so that 35 the legs of the patient will extend over part of the leg exercising frame, and means carried by the leg exercising frame for causing the legs to move back and forth and be bent during the movement.

WILLIAM S. HAWLEY.
